UNITED STATES PATENT OFFICE.

GIDEON SUNDBACK, OF, MEADVILLE, PENNSYLVANIA, ASSIGNOR TO HOOKLESS
FASTENER COMPANY, A CORPORATION OF PENNSYLVANIA.

FASTENER.

REISSUED

Original application filed April 2, 1917, Serial No. 159,139. Divided and this application filed August 15, 1921. Serial No. 492,621.

To all whom it may concern:

Be it known that I, GIDEON SUNDBACK, a subject of the King of Sweden, and resident of Meadville, in the county of Crawford and State of Pennsylvania, have invented certain new and useful Improvements in Fasteners, of which the following is a specification.

This invention relates to fasteners of the 10 type wherein closures for the edges of a garment, curtain, bag, tent or the like are to be separably connected by a fastener which embodies a sliding operating device which separates the edges when moved in one direction and closes them when moved in the 15 opposite direction. Hitherto in the use of such fasteners, the degree of separation permitted has been limited by the fact the edges had to remain joined at at least one 20 point. By a novel arrangement of parts, involving the use of a flexible extension member, I have made it possible to secure as wide an opening as may be desired. By reason of this advantage, my invention is particularly applicable to such articles as corsets, spats, curtains, etc., where wide separation without actual disconnection is required. This application is a division of 25 my previous application for fastener, Serial 30 No. 159,139, filed April 2, 1917, Patent No. 1,403,988, January 17, 1922.

With these and other objects in view, I have devised the apparatus embodying my invention, as described in the following specification and illustrated in the accompanying drawing, of which—

Fig. 1 is a plan view of the device as ordinarily applied,

Fig. 2 is a detail plan view of the fastening means,

Fig. 3 is a perspective view of the device attached to a corset,

Fig. 4 is a side elevation of a spat showing the application of the device thereto,

Fig. 5 shows a different mode of applying the device to a spat,

Fig. 6 is an inverted plan view of a spat showing the degree of separation permitted by the device, and

Fig. 7 is a side elevation of the device attached to a curtain.

Fig. 8 shows the locking device in open position to be used as an actuating means.

Fig. 9 is a side view of Fig. 8.

1 represents a body having edges 2 which 55 are to be closed. The fastener embodies stringers 3, 3 composed of tapes having corded edges 4, 4 to which the interlocking members 5 are clamped in staggered relation. A sliding hollow Y-shaped cam 6 fits over members 5 and travels along edges 2 to engage or disengage the interlocking members 5 on the respective edges 2. Cam 6 has slotted sides through which the tapes extend laterally but which retain members 5 against 60 forces tending to separate edges 2. The tapes of stringers 3 are stitched respectively to the separate portions of body 1 beyond edges 2. One or both of the stringers 3 are provided at the closing end with stop members 7 passing within the slider 6, and engaging the latter to prevent further movement.

Beyond the end of body 1 stringers 3, 3 are extended to constitute extensions 8, and 75 these extensions are connected at their outer ends by link members 9 joining the respective stringers. Extensions 8 are preferably provided with interlocking members 5, and are of such a length that when slider 6 is 80 stopped by link members 9, the body 1 can be separated to such an extent that the extensions 8, owing to their flexibility, will straighten out end to end. In the fasteners as heretofore used, without extensions, the 85 end members 9 would directly connect the lower end of body edges 2, and slider 6 would consequently not go the entire length, thus preventing complete separation of edges 2. By reason of extensions 8 receiving slider 90 6, as much opening may be secured as desired, depending on the length of extensions 8. As the free edges of the extension 8 straighten out end to end, the maximum degree of separation of the lower edges of body 1 will be about twice the distance of the top of slider 6 from the lower edges of body 2.

In Fig. 3, the extension principle is applied to a boned edge corset, and permits 100 the corset to be put on or taken off without requiring complete opening. 10 is the usual lacing, and 11 is the fastener of this invention. The body of the corset ends at 12, and 13 are the extension members. When 105 the slider is moved down to the lower portion of the extensions 13, these can stretch out end to end to such an extent as to per-

mit the corset to be stepped into or out of without complete separation, and when the slider is pulled up the corset will be quickly and firmly fastened.

5 In Fig. 4 is shown an application of the extension to a spat, in which 14 represents the body of the spat provided with the fastener as shown, the instep strap 15 being split and carrying the stringer extensions.

10 When the slider 16 is moved down to the extreme bottom, strap 15 stretches out end to end and makes such a wide opening that the spat can easily be slipped on and off the foot without disconnecting the strap 15 from the body, as is the usual custom. In Fig. 5 the strap is not split as in Fig. 4, and only one stringer is connected thereto, the strap also being sewed only to the body

15 14 on the side to which the stringer is attached. Thus the slider can go down to the lower end of the stringers as in Fig. 4, and the stringers will stretch out end to end so as to provide the wide opening. Inasmuch as the body of the spat 14 overlaps 20 the free side of the strap, it makes no difference that the strap is not attached to the body on both sides.

In Fig. 7 the extension principle is applied to a curtain 17 carried by a body or support 18, such as a tent, automobile top, etc., and the stringer extension 19 is sufficiently long to permit curtain 17 to be swung around relatively to the support when separated. The other stringer extension 35 appears as attached to body 18 for its entire length, but it may be partly free if desired. This arrangement is a decided advantage in enabling the curtain to be rolled up.

40 The locking means shown in Figs. 8 and 9 comprises a plate 22 attached to the reinforcing loop 23 of the slider by means of the extensions 29, which are bent to lie within the loop 23 and serve as a pivot about which the plate 22 may be moved. The plate also has spring wings 24 which resiliently engage the ends of the slider channel when the plate 22 is swung downwardly from the position shown in Fig. 8 to 45 that shown in Figs. 1 and 2. At this time the wings 24 close over the ends of the slider channels and obstruct passage of the stop members 7 as shown in Fig. 2. 25 is a slot in the plate 22 to increase its resiliency, and 26 are buttons or projections to furnish a finger hold. One projection 26 fits into the slot 27 in the bottom of the slider. 28 is a fastening which secures the loop 23 to the doubled slider body. The slider can be positively actuated in either direction through the plate 22.

What I claim is:

1. In a body having meeting edges, means secured to and distributed along the length 65 of said respective edges for connecting the

same, means movable progressively along said edges to control said connecting means, and an extension constituting in effect a continuation of said edges for receiving said movable means when said edges are disconnected, whereby to increase the separation. 70

2. The combination with a separable body portion, of stringers on the adjacent edges thereof extending substantially beyond the body portion, connecting members on the stringers, means sliding on the stringers to control the connection, and means beyond the body portion for limiting opening movement of said sliding means after it 75 has passed substantially beyond said body portion.

3. The combination with a separable body portion, of stringers on the adjacent edges thereof extending beyond the body, means 80 on the stringers for connecting the body portion, means sliding on the stringers to control the connection, said means when slid beyond the body substantially increasing the separation of the body portion without 85 completely disconnecting it. 90

4. A body having meeting edges, members for connecting said edges, an operating device movable on said edges to control said members, and an extension for receiving said 95 operating device when said edges are separated whereby to increase the separation. 95

5. A fastener having stringers longer than the opening to be closed, fastening members, and operating means slidable upon the 100 lengthened portions of the stringers when the fastener is opened.

6. A pair of body portions having relatively stiff edges, flexible stringers secured to and extending beyond said edges, means 105 connecting the ends of said stringers, and means on said stringers for progressively connecting and disconnecting said edges and permitting said stringer extensions to stretch out end to end when said body portions are 110 have maximum opening.

7. A body portion of material provided with an opening therein, members for closing the opening, a slider movable along the edges of the opening and adapted to control 115 said members, an extension secured to the body portion of said material and along which the slider is adapted to be moved to increase the separation of the opposite edges of the opening and means for locking said 120 slider in position with said opening closed.

8. A slider comprising a body having channels to receive stringers, and locking means carried by the slider for locking the stringers. 125

9. A slider comprising a body having diverging channels, and locking means for obstructing at least one of said channels.

10. A slider comprising a body having channels to receive stringers and means 130

pivoted thereon functioning as an actuator in one position and as a slider lock in another position.

11. A fastener comprising two stringers carrying connecting members, a sliding device for operating said connecting members, a stop member on one of said stringers adapted to limit movement of said sliding device, and means carried on said sliding device and cooperating with said stop member for locking the fastener.

12. A body portion of material having an opening therein, members for closing the opening, a slider movable along the edges of the opening and adapted to control said members, an extension secured to the body portion of the material and along which the slider is adapted to be moved, said extension also being provided with an opening and closing members therefor controlled by the slider, the opposite edges of the extension opening, being permanently secured on the end of said opening remote from the body portion.

13. A body portion of material provided with a slit, members for closing the opposite edges of said slit, a slider movable along said edges for progressively controlling said members, an end member on at least one of said edges for limiting the closing movement of said slider, and locking means adapted to retain said end member within said slider.

14. A body portion of material provided with a slit, members for closing the slit, a slider movable along the edges of said slit for progressively controlling said members

and a locking means for retaining the slit closed and preventing movement of said slider relative to said members.

15. A body of material provided with a slit, means comprising a slider movable along the edges of the slit for progressively opening or closing the slit, a locking device for said slider adapted to prevent the material being pulled through the slider.

16. A spat provided with a longitudinal slit along one side, fastening members for closing said slit, and a slider movable along the edges of said slit for controlling said fastening members, an extension loop secured to the opposite sides of said spat and adapted to extend under the wearer's instep, said loop being slit in continuation of the longitudinal slit in the spat and provided with connecting members adapted to be controlled by said slider, the slit in said extension loop being of a length sufficient to permit removal of said spat.

17. A body of material adapted to extend on opposite sides and over an edge of an object, said body of material being provided with a slit extending over the edge and long enough to permit removal of the material from said object when the slit is opened, a flexible fastener for said slit and a slider progressively controlling said fastener, and movable over the edge of said object and in different planes.

Signed at New York, in the county of New York and State of New York this 12th day of August, A. D. 1921.

GIDEON SUNDBACK.
